SEAMLESS KNITTING AND RESULTING
PRODUCT

Sidonia Schweig, Jamaica, N. Y.

Application March 13, 1936, Serial No. 68,652

2 Claims. (Cl. 66—175)

My present invention relates to a method of knitting and the product resulting therefrom, and aims to devise a method of the general character indicated, which is simple and economical to practice, requires no equipment other than a standard flat knitting machine, and which results in a very attractive and inexpensive garment.

Before describing my invention in detail, it is deemed advisable, briefly, to refer to the prior art to which the present invention relates, and to point out the shortcomings thereof, and the manner in which the present invention overcomes such shortcomings.

It has heretofore been the practice in producing seamless knitted garments such as blouses, skirts, etc., to make the same by hand rather than by machine, for the reason that while tubular material could be produced on either a circular machine or a flat machine with certain attachments, it was not possible to shape or fashion the garment, and the same remained equal in width throughout its length. However, I have discovered that by means of the present invention knitted garments can be made on a flat knitting machine by manipulations hereinafter referred to more in detail.

In the accompanying specification I shall describe an illustrative embodiment of the method of the present invention, and in said specification and in the annexed drawing I shall describe and show one type of garment which can be produced by means of the method of the present invention.

Other objects and advantages of the present invention will become obvious to those skilled in the art to which the present invention relates as the detailed description thereof progresses.

In the annexed drawing:—

Fig. 1 is a plan view of a garment produced by means of the present invention;

Fig. 2 is an enlarged, fragmentary view of one of the side edges of the garment showing the courses taken by the wales in the production of the garment.

Fig. 3 is a similar view of the point of joinder between the blouse and sleeve portions of the garment; and

Fig. 4 is a similar view showing the manner in which the skirt and blouse portions of the garment are joined together.

Referring now more in detail to the aforesaid illustrative embodiment of the method of the present invention, I proceed by knitting a predetermined number of rows, generally indicated by reference character 10 in the drawing, upon a flat

knitting machine provided with a standard special travelling lock known as a tubular lock in order to obtain knitted material in tubular form. Upon reaching a predetermined point, indicated at 11 in the drawing, I remove from the needles at the outer extremities of the knitted fabric, a predetermined number of loops or stitches and move said loops inwardly toward each other and place the same upon the needles adjacent those which previously carried said loops. The result of this operation is to reduce the width of the fabric when the knitting is continued. In Fig. 2 of the drawing, which shows one of the edges or ends of the tubular material, it will be noted that during the knitting, of the portion 10 of the material, a definite area thereof includes six (6) wales indicated as a, b, c, d, e, and f, but that upon reaching and thereafter passing the point 11 and continuing the running of a predetermined number of courses, indicated as 12, the same area of material includes only four (4) wales bearing reference characters g, h, i, and j. Thus, the width of the garment is reduced so as to get the proper shape, it being obvious that a skirt cannot be equal in width throughout its length.

After knitting the portion 12, the point 13 is reached, at which time the width of the garment is further reduced by repeating the operations carried out at the point 11. These operations are continued until the entire skirt 14 is completed and the upper edge thereof has been brought down to the desired waist width. If desired, the lower edge of the skirt may be finished off in any manner such as by providing the same with a crocheted portion 15. The blouse 16 is likewise knitted by starting at the upper edge and gradually reducing the width thereof at the points 17 until the lower edge thereof is equal in width to the upper edge of the skirt 14. If desired, the neck of the blouse may be provided with a crocheted or any other decorative portion 18.

Finally, the sleeves 19 are made by the same method except that instead of reducing the width thereof as the knitting progresses from both edges, as in the case of the skirt and blouse, stitches or loops are moved inwardly only from one edge thereof at a multiplicity of points 20. By so doing, one edge of the sleeve is in a straight line while the other edge is shaped. If desired, the sleeves may be provided with cuffs or other edges 21.

In Fig. 3 of the drawing I have shown the manner of joining the sleeves 19 with the blouse 16, this being preferably effected by picking up the

adjacent stitches of the sleeves and blouse, and crocheting them together at the point 22.

While the blouse and skirt may be joined together in a manner similar to the sleeves and blouse, that is, by crocheting them together, I prefer, in order to permit the blouse and skirt to be worn separately, to utilize the method of joining illustrated in detail in Fig. 4 of the drawing.

I provide the upper edge of the skirt 14 with 10 a row of crocheting 23 from which there branches front link portions 23' and 23'', and a rear link portion 23''', the upper ends of all of which links are connected by a row of crocheting 24. The lower edge of the blouse 16 is likewise provided with a row of crocheting 25 from which branch front links 25' and 25'' and rear links 25''', the lower edges of which are connected by a row of crocheting 26. The links on the blouse and skirt are interlocked by means of 15 a flexible band 27, which takes a course passing to the rear of the links 23', 23'', 25' and 25'', and in front of the links 23''' and 25'''. The ends of the flexible band 27 may, if desired, be connected by snap fasteners (not shown). Thus 20 the blouse and skirt are only temporarily connected and obviously may be worn separately, if desired.

This completes the description of the aforesaid 30 illustrative embodiment of the method of the present invention, and the garment resulting from the practice thereof. It will be noted that

inasmuch as no equipment other than a standard flat knitting machine provided with a tubular lock is required for the practice of this method, the same is very simple and inexpensive to perform, and results in a garment which is inexpensive and which is properly shaped and very attractive.

Other objects and advantages of the present invention will be obvious to those skilled in the art to which the present invention relates.

10

What I claim as my invention is:

1. The method of making a garment which consists in the steps of knitting a seamless skirt and blouse, each of gradually reducing width, providing said skirt and blouse with connecting means by crocheting at the waist edges thereof a plurality of loops, and thereafter connecting said skirt and blouse by positioning the loops of each adjacent each other and threading a tape therethrough.

15

2. The method of making a garment which consists in the steps of knitting a seamless skirt and blouse, each of gradually reducing width, providing said skirt and blouse with connecting means by crocheting at the waist edges thereof a plurality of connected front and rear links, and thereafter connecting said skirt to said blouse by interlocking the links on each and threading a flexible band through said connecting means intermediate the front and rear links thereof.
